The ornamental design for a “combined luggage tag and lottery number generator,” as shown and described.

DESCRIPTION

FIG. 1 is a front view of a combined luggage tag and lottery number generator incorporating my new design without the attachment strap;

FIG. 2 is a rear view thereof without the attachment strap;

FIG. 3 is a side view thereof without the attachment strap, the opposite side being a mirror image;

FIG. 4 is a view from above thereof without the attachment strap;

FIG. 5 is a view from below thereof without the attachment strap; and,

FIG. 6 is a perspective view thereof with the attachment strap. The rear surface of the strap is flat and unornamented. For ease of illustration, the strap has been omitted in FIGS. 1–5.
